UNITED STATES PATENT OFFICE.

SAMUEL JEWELL, OF NEGAUNEE, MICHIGAN.

SAFETY CROSS-HEAD FOR MINE-HOISTS.

1,252,122.

Specification of Letters Patent.

Patented Jan. 1, 1918.

Application filed January 25, 1915. Serial No. 4,196.

To all whom it may concern:

Be it known that I, SAMUEL JEWELL, a citizen of the United States of America, and a resident of Negaunee, county of Marquette, and State of Michigan, have invented certain new and useful Improvements in Safety Cross-Heads for Mine-Hoists, of which the following is a specification, reference being had to the accompanying drawings, forming a part thereof.

My invention relates to cross-heads for mine hoists and has for one of its objects to provide a safety cross-head that shall be simple and durable in construction, positive and reliable in operation, and adapted to not only prevent the cross-head from dropping in case the rope or cable breaks, but also to eliminate the possibility of its becoming accidentally stuck or "hung up" in the shaft.

Other objects and advantages of my invention will be set forth hereinafter, and in order that my invention may be thoroughly understood, I will now proceed to describe the same in the following specification and then point out the novel features thereof in appended claim.

Referring to the drawings:

Figure 1 is a front elevation of a cross-head arranged and constructed in accordance with my invention.

An end elevation of the same is shown in Fig. 2.

Fig. 3 is a sectional elevation showing the cross-head in its set position and

Fig. 4 is a sectional plan view, taken on the line 4—4 of Fig. 3.

The cross-head illustrated is of the type used in the mine hoists and is adapted to be raised out of or lowered into a shaft with a rope or cable, the load being supported by a bucket or other suitable carrier which is connected to the rope or cable, after it extends through a guide in the cross-head.

Cross-heads of this type are very heavy and may do considerable damage if one is accidentally hung up in the shaft for any cause and then drops onto the bucket after the latter has been lowered away from it. It has been my aim to provide a safety device for preventing accidents of this character and also for preventing the dropping of the bucket in case the rope or cable should break above the cross-head.

As clearly shown in the drawings the cross-head comprises a frame built up of

flanged side runners 10 and 11 which are adapted to coöperate with guideways 8 and 9, and a pair of transverse box beams 12 and 13. Secured to the box beam 12 and extending downwardly between the parts of the box beam 13, is a sleeve 14 through which the bucket cable or rope 15 extends. This sleeve may be secured in any suitable manner, as for example by being screwed into a block 16 as clearly shown in Fig. 3, and it may be conveniently formed of a pipe section. It has a slot 17 in one side through which a pawl 18 extends as hereinafter explained.

A pair of yokes or clevises 19 and 20 are secured in an upright position between the sides of the box beam 13 and are located one on each side of the sleeve 14 which is in the center of the cross-head. A horizontal yoke 21 having a ring-shaped center 22 through which the cable 15 extends, is suspended by links 34 and 35 as explained below and has connected to it spring guide rods 23 and 24 which extend through suitable holes in the top of the clevises 19 and 20.

Mounted on the spring guide rods 23 and 24 between the yoke 21 and the top of the clevises are helical springs 27 and 28 which tend to push the lever 21 downwardly as hereinafter explained.

Near the respective ends of the box beam 13 are a pair of cross pins 30 and 31 on which are mounted cam jaws 32—33. The cam jaws are actuated by the yoke 21 to which they are connected by links 34—36 and 35—37. The arrangement of parts is such that the links 36 and 37 are rigidly fixed relative to the cam jaws 32 and 33, either directly or through the pins 30 and 31, and consequently when the yoke 21 is moved upwardly in opposition to the springs the cam jaws are rotated on their pivots and are released from the guideways 8 and 9 with which the flanged shoes 10 and 11 co-operate.

A collar 39 is clamped to the sleeve 14 near its lower end and supports the pawl 18 which is pivotally mounted upon it and extends upwardly through the slot 17 in the sleeve. Secured to a pin 40 on which the pawl 18 is pivoted is a lever 41 which extends through a guide strap 42 on the shoe 10 and is adapted to be actuated manually for the purpose of releasing the pawl.

The shoes 10 and 11 have slots 43 and 44

through which the cam jaws 32 and 33 extend and the outer surfaces of the cam jaws are notched or toothed as shown at 45 and 46 to enable them to more firmly grip the timbers of which the guideways 8 and 9 are usually comprised.

The cable 15 is formed into a loop 48 below the cross-head and its end is doubled back on itself and extends upwardly into or 10 beyond the sleeve 14. The end is securely fastened to the body of the rope by rings or 15 clasps 50, at least one of the clasps, as clearly shown in Fig. 3, being located above the pawl 18. The pawl is thus able to engage 20 the ring and prevent the rope from being pulled out of the cross-head in case the rope should be broken above the head. A ring or 25 collar 51 is mounted on the rope under the ring-shaped center 22 of the yoke 21 and 30 above one of the rings 50. This collar prevents the cross-head from falling and, since it engages the yoke 21, the entire weight of 35 the cross-head tends to compress the springs 27 and 28, move the lever upward relative to 40 the box beam 13, and swing the cam jaws 32 and 33 into their released position as shown in Fig. 1. The yoke 21 constitutes an inter- 45 connecting and actuating bar for the links 36 and 37.

The operation of the cross-head is as follows: Assuming that the parts occupy the positions in which they are shown in Fig. 1, a load being supported by the loop 48 of the cable which is being lowered, if under 50 these conditions everything operates in a normal manner the shoes 10 and 11 will slide on the guideways 8 and 9 and the cam jaws will be released and will not engage the guideways. If, however, the rope should 55 break the load will immediately tend to pull the rope out of the cross-head and this will be prevented by the engagement of the pawl 18 with the ring 50, which is above it, as shown in Fig. 3. The load on the cable tends 60 to travel faster than the cross-head on account of the friction between the shoes and the guideways, and consequently the collar 65 51 will cease to support the weight of the

cross-head with the result that the springs will push down the yoke 21 and set the cam 50 jaws against the guideways. The cross-head and the load will thus be brought to rest.

Should the cross-head stick, it will be forced downwardly by the engagement of one of the rings 50 with the pawl 18 for a 55 short distance sufficient for the safety cam jaws, which are at once released, to be set into the guideways.

When the bucket or carrier is being raised the springs will be compressed and the jaws 60 held in their released positions under normal conditions the same as for lowering.

In case it is desired to pay out the rope or cable through the cross-head as for example, to form a new loop, the pawl may be released 65 by the lever 41.

The details of the structure illustrated may be varied within the spirit and scope of my invention and I intend that only such limitations be imposed as are indicated in the 70 appended claim.

What I claim is:

A safety cross-head comprising a frame having shoes adapted to coöperate with stationary guideways, a rope guide sleeve having a slot, a latch pivotally mounted on the sleeve and extending through the slot, a hand lever for releasing the latch, a transverse yoke having an opening for the rope and yieldingly suspended from the frame, 80 springs tending to force the yoke downwardly, a pair of clutch jaws oppositely connected to the yoke at its respective ends and adapted to be forced outwardly into engagement with the guideways by the springs, 85 the weight of the cross-head being applied to the yoke to release the clutch jaws under normal operating conditions.

In testimony whereof I have hereunto set my hand this 13th day of Jan. 1915, in the 90 presence of two subscribing witnesses.

SAMUEL JEWELL.
